234,054

OIL-FIRED RADIANT SPACE HEATER

Malcolm W. Patrick, Danville, and Joseph W. Adams, Westlake, Ohio, assignors to Bettcher Manufacturing Corporation, Cleveland, Ohio

Filed Apr. 5, 1973, Ser. No. 348,640

Term of patent 14 years

Int. Cl. D23—03

U.S. Cl. D23—93

FIG. 1

FIG. 2

FIG. 3

FIG. 4

FIG. 1 is a side elevation of the oil-fired radiant space heater embodying our design.

FIG. 2 is a top plan view of said heater.

FIG. 3 is a bottom plan view of said heater.

FIG. 4 is an end elevation of said heater viewed from the right as shown in FIG. 1.

The oil burner is shown in FIGS. 1, 2 and 3 in broken lines for illustrative purposes only.

We claim:

The ornamental design for an oil-fired radiant space heater, as shown and described.
